UNITED STATES PATENT OFFICE

WILLIAM F. AID, OF CLEVELAND, OHIO

GUARD RAIL

Application filed October 26, 1931. Serial No. 571,095.

The present invention relates to guard rails that are used in advance of facing point switches, opposite frog points and around curves, and which, in such positions, cooperate with the main or traffic rail to guide or deflect the wheel flanges and prevent derailments. In accordance with present practice, the guard rail usually comprises a piece of ordinary track rail that is spiked to the ties or is secured to the traffic rail by means of clamps or fillers and bolts, so that it is expensive to install. Also the many separate parts employed for securing the guard rail in place are apt to work loose and stretch, when subjected to the great weight and high speed of railway equipment of the present day, and so permit a dangerous increase in the width of the flangeway between the guard and traffic rails. Special guard rails formed of integral steel castings are expensive and cannot be readily repaired.

The present invention provides a unitary guard rail structure, preferably formed of rolled or wrought steel, and comprising a rail and tie plates and preferably also braces, all welded together into a one-piece structure which can be shipped as a unit and readily installed with little labor and without the use of separate clamps and bolts. The invention consists in the construction hereinafter set forth, illustrated in the preferred forms in the accompanying drawings and more particularly pointed out in the appended claims.

In the drawings:

Figure 1 is a plan view of a guard rail structure embodying the present invention.

Fig. 2 is a side view of the structure shown in Fig. 1.

Figs. 3 and 4 are sections on the lines 3—3 and 4—4 respectively of Fig. 1.

Figs. 5, 6 and 7 are cross sections illustrating modifications.

Fig. 8 is a side elevation of another form.

Fig. 9 is a section on the line 9—9 of Fig. 8.

Fig. 10 is a plan view of a further modification.

In the form shown in Figs. 1 to 4 inclusive, the guard rail comprises a piece 10 of standard rolled rail provided with the usual deflected end portions and having its outer base

flange cut away except at the deflected ends. A series of tie plates 11 preferably formed of rolled steel extend beneath and are permanently welded to the base of the rail 10, preferably by means of fillet welds 12 extending along the edges of the plates.

Rail braces 13 are secured to the inner ends of some, or, if desired, to all of the plates. In the form shown in Figs. 1 to 4 inclusive, the rail braces are formed integral with the plates, each being forged from an extension that is folded over the inner end of the plate and shaped to provide an upwardly inclined bracing strut 14 of inverted U-shape in section and having laterally extending base flanges 15 at the lower edges of its side walls. The strut and base flanges of each brace fit snugly against the underside of the head and the upper side of the base of the rail 10 and against the rail web, and are welded to the rail preferably by fillet welds 16 extending along their edges.

The portions of the base flanges 15 that extend beyond the rail base, contact with the inner ends of the tie plates 11, and these contacting portions are provided with holes 17 for receiving spikes 18, as indicated in dotted lines in Fig. 3. The tie plates of the unitary guard rail structure are adapted to extend beneath the main or traffic rail 19 and are provided with holes 20 for receiving spikes 21 that hold the traffic rail in position. The plates can also be provided with ribs or shoulders 22, as shown in Fig. 3, for engaging the outer base flange of the main rail. Foot guards 23 formed of pieces of rolled steel plate having inclined end portions 24 are welded to the deflected end portions of the rail 10 by fillet welds 25.

The form shown in Fig. 5 is similar to that previously described except that thin wedge-shaped pieces or shims 26 extend between the tie plates 11 and the base of the guard rail 10 and are permanently welded to these parts, the wedges or shims are adapted to extend beneath the main or traffic rail to cant, so that the treads of the car wheels will have a bearing entirely across the head of the rail.

In the form shown in Fig. 6, the tie plates are provided with raised portions 27, and the

guard rail 10' secured thereto can then be of less height than the main rail if desired. In the construction shown in Fig. 7, the rail braces each comprise base and vertical flanges 5 28 and 29, and an inclined strut 30 integral therewith. The flanges fit the head, base and web of the rail and are welded thereto as indicated at 31, and extensions 32 of the base flanges are welded to the inner extended ends 10 of the tie plates.

The form shown in Figs. 8 and 9 is provided with a guard rail 33 of special rolled shape and comprising an inclined portion 34 having a base flange 35 and a vertical flange 15 36 depending from its upper edge. The tie plates and braces are like those shown in Figs. 1 to 4 inclusive except that the shape of the braces 13' are modified to fit against the inclined portions 34 of the guard rail. This 20 inclined portion is cut away between the braces to provide openings 37 that permit the escape or ready removal of snow and ice from the flangeway and space between the guard and running rails.

25 In the structure shown in Fig. 10, the guard rail 38 is formed of a piece of standard rail, its base is straight or substantially so, the outer base flange being cut away throughout its length, and the flares at the 30 ends of the rail being formed by planing the ball or head of the rail. In this form, combined plates and braces such as previously described alternate with plain tie plates 39, and the plates are all of the same size and 35 are all parallel or substantially so. If desired, all of the plates could be combined with braces or all plain plates could be employed. In this form the plates are provided with ribs or shoulders 22 for engaging the outer 40 base flange of the running rail.

The present invention provides a unitary or integral guard rail structure, which is inexpensive to manufacture, repair and install, and which can be shipped as a unit free from 45 loose parts. The structure also obviates the necessity of employing clamps, bolts and the like for maintaining the guard and main rails in proper relative position. Changes may be made in the details set forth without departure from the scope of the appended 50 claims.

I claim as my invention:—

55 1. A unitary guard rail structure comprising a guard rail and a series of tie plates and rail braces welded to the guard rail with the tie plates projecting therefrom and adapted to extend beneath the main rail and having means for determining the spacing of the main and guard rails, substantially as described.

60 2. A unitary guard rail structure comprising a guard rail and a series of tie plates and rail braces, the tie plates being welded at their edges to the lower face of the guard rail base and projecting therefrom to extend

beneath the main rail, and the braces being secured to the inner ends of the tie plates and welded at their edges to the rail, substantially as described.

3. A guard rail structure, comprising a 70 rail, and a series of tie plates and rail braces secured together and permanently welded to the rail with the tie plates projecting outwardly therefrom and having holes in their projecting portions for the spikes that engage the inner and outer base flanges of the main rail, substantially as described.

4. A guard rail structure, comprising a 75 rail, tie plates extending beneath and welded to the rail base, and braces integral with the inner ends of tie plates and each having base flanges and an inclined strut engaging and welded to the head, base and web of the rail, substantially as described.

5. A guard rail structure comprising a 80 rail, a series of tie-plates and rail braces secured together and welded to the rail with the tie plates projecting therefrom to extend beneath the main rail, and foot guards welded to the ends of the guard rail, substantially 85 as described.

6. A guard rail structure comprising a rail, a series of tie plates and rail braces secured together with the braces welded to the rail, and wedge-shaped shims extending between 90 and welded to the tie plates and the rail, the tie plates and shims being arranged to extend beneath the main rail, substantially as described.

7. A guard rail structure comprising a 100 guard rail, and a series of tie plates, rail braces, and wedge shaped shims, the shims extending between the tie plates and guard rail and having portions adapted to extend beneath a main rail. 105
